SLASHER

Ernest K. Whitener and Thomas F. Suggs, Gastonia, N. C., assignors to Cocker Machine and Foundry Company, Gastonia, N. C., a corporation of North Carolina

Application April 19, 1938, Serial No. 202,993

12 Claims. (Cl. 28—28)

This invention relates to slashers, and, more particularly to the drives therefor. Slashers as previously employed for sizing cotton yarns at low speeds, and subsequently also used for similar treatment of synthetic yarns, were not designed, built or expected to meet the difficulties encountered in using the same for sizing synthetic yarns at either low or high operating speeds. The principal reason for this trouble was resultant upon the difference in condition of cotton and synthetic yarns while wet with sizing solution, namely the wet cotton yarns retain practically the same tensile strength, whereas wet synthetic yarns become soft and are easily stretched or damaged when subjected to any undue strains or jerking movement while in such condition. Provision also had to be made for preventing "over-run" of the slasher section beams, that caused yarn tangling, when necessary to stop the slasher for any reason. At low operating speeds, only a small amount of braking action against turning of the beams was necessary, but for higher speeds the amount of braking action had to be proportionately increased which, when handling synthetic yarns in the wet and consequentially weakened condition entailed stretching thereof and incidental damage to said latter species of yarn.

Furthermore, driving of the loom beam on slow speed slashers has usually been effected by means of felt-covered slip friction plates with associated weight and lever adjustments, which have proven in practice inefficient. The increasing speed at which these friction plates worked against each other in building from an empty to a full beam generated excessive heat, and wound the beams with varied degrees of yarn tension and beam density. With known friction means it is practically impossible to secure a uniform tension in the warps initially, or to maintain a definite even tension throughout the sizing operation, since, on the one hand, the belts relied upon to produce the restraining effect cannot be adjusted with absolute accuracy, and since, on the other hand, the gradual decrease in the diameter of the beams and weight of the yarn as the sizing operation proceeds is attended by a corresponding increase in the pull on the warps. These differences in tension manifest themselves in the fabric subsequently woven from the processed warps, causing unevenness in texture and variations in weight. Moreover, since with slasher creels of the usual construction, the tension imposed on the warps is dependent upon the size and weight of the supply beams, a definite speed limit is set

beyond which the slashers cannot be safely operated without danger of frequent warp breakage. Hence a limit is set, upon the amount of yarn which can be processed during each run of the slasher, with corresponding curtailment in production. Another disadvantage due to unevenness of tension is that the beams, under the least restraint, run out faster than the others, with resultant wastage of the unused warps on the partially exhausted beams.

An important object of this invention is to overcome the above noted disadvantages by providing a novel automatically-controlled two speed drive, preferably for rayon slashers, also valuable in the operation of cotton yarn slashers, whereby the transition acceleration, from an average low-speed yarn travel of two yards per minute to the average twenty to sixty yards operating speed, is made uniformly gradual and vice versa, while the "jerking" action imposed on the yarns by conventional drives is prevented.

Another object is to provide slashers of the indicated type with means whereby, when stopping the slasher while operating at its maximum speed, the yarn travel speed is automatically, gradually, and uniformly, brought from its maximum operating speed to a dead stop without any over-run of the section beams whatsoever or the necessity for applying any increased amount of braking action.

A further object of this invention is the provision of compensative means, whereby the speed of the friction plates, working against each other, is automatically kept uniform throughout the building of the loom beam, and thereby resulting in a better weaving beam of more uniform yarn tension and beam density, than is obtainable by conventional loom beam drives for slow speed slashers.

A still further object is to electrically-control the two-speed main drive by provision of appropriate switch stations at both sides of each cylinder unit, whereby individual starting, stopping and varying the operating-speed of the slasher can be positively effected.

With the above recited general objects in view, and others of a tributary character, this invention consists in certain novel and peculiar features of construction, and the organization of cooperative parts as hereinafter disclosed and claimed.

In order that the same may be clearly understood, reference is to be had to the accompanying drawings illustrating a practical embodiment of the invention, and wherein like characters of

reference are applied to corresponding parts in the respective illustrations.

Fig. I is a plan view of the head-end of a slasher including the automatically-controlled two-speed operating and compensating friction drives of this invention.

Fig. II is a somewhat larger scale plan view of the compensating loom beam friction drive, apart from the head-end of the slasher.

Fig. III is a vertical section on the line III—III in Fig. I, but drawn to increased scale for the purpose of clearness; and,

Fig. IV is a wiring diagram showing how the two-speed operating drive of this invention is electrically controlled.

Referring in greater detail to the drawings, and more particularly to Fig. I, the head-end of a multiple-cylinder high-speed rayon slasher is comprehensively designated by the numeral 1; the same comprising side frames 2, secured together in spaced relation by girts 3 and cross-ties 4. The cross-ties 4 afford rigid support for the slasher main drive motor 5, in turn operatively coordinating a succession of variable-speed devices 6, 7 and 8, through the medium of a multiple-belt 9 and chain drives 10, 10' to the shaft 11 for operating the calender roll 12 by tooth gears 13, 14, in an obvious manner.

A two-speed reversing motor 15, by means of a chain drive 16 to a shaft 17 having thereon a gear 18, in mesh with a gear 19 on the adjusting-screw 20 of the variable-speed transmission 8, serves to operate the latter in accordance with known practice; while a sprocket-and-chain drive 21 from the screw 20 coordinates the adjuster screw 22 of the variable-speed device 1, for simultaneous operation. A belt or sprocket-and-chain drive 23 operatively connects the shaft 11 with the variable-speed device 8 for regulating the yarn tension between the drying cylinder (not shown) and the leading calender roll 12; while it is to be noted the variable-speed devices 6 and 7 are under the control of a mechanically actuated limit-switch 24.

The collecting beam 25 is provided at one end with a conventional friction drive device 26, associated differential 27, and an operatively coordinated variable-speed device 28. It is to be particularly observed that one of the differential power shafts 29 is, preferably, driven by a sprocket-and-chain drive 30 from the friction device constant drive member 31, through the medium of a clutch 32, and chain drive 31'. The other power shaft 33 of the differential 27 is operated from the slip side of the friction device 26 by a sprocket-and-chain drive 34; and it will be obvious that the amount of "slip" of said device is determined by the ratio between the sprocket 35 and sprocket 36. The sprockets 35 and 36 driving the differential sprockets 37, 38 in the same direction will cause the differential shaft 39 to remain stationary.

When thread or yarn *y* commences to build-up on the collecting beam 25, the friction device 26 automatically changes the ratio between the sprockets 35 and 36, and, consequently, the speed of the differential sprockets 37 and 38, thus starting the shaft 39 to rotate in a clockwise direction. As a result, the rotation of the shaft 39 is communicated by a sprocket 40, and chain drive 41, to the sprocket 42 on the adjuster-screw 43 of the variable-speed device 28, whereby said screw is rotated in a like direction, thus altering the speed of the variable shaft 44 of the device 28. From the shaft 44, the change of

speed is transmitted by a sprocket 45 and chain drive 46, to the sprocket 47 of the friction drive device 28, whereby the speed of the collecting beam 25 is automatically varied as the yarn *y* builds up thereon.

Referring now more particularly to Figs. II and III, it will be readily seen that as the collecting beam 25 becomes filled with yarn *y*, the variable shaft 44 will be at its lowest speed, whereupon it is necessary to re-set said variable-shaft to its highest speed, when an empty collecting beam 25 is inserted and started. This requirement is preferably accomplished by the means now to be described. The bearing 48 for the shaft 49 of the clutch 32 is provided, at one 15 side, with a rigid half-clutch 50 for holding the sprocket 51 of the chain drive 30 stationary; which, consequently, arrests the chain drive 30 and the sprocket 37, and, thereby, causes the differential shaft 39 to revolve in an anti-clockwise 20 direction. This anti-clockwise rotation of the shaft 39 will, by means of the sprocket 40, chain 41, and sprocket 42, revolve the variable-speed adjuster-screw 43 in a like direction, and cause the variable-speed shaft 44 to be accelerated to 25 its maximum high speed. Rotary motion is imparted to the variable-speed device 28 by means of a sprocket 52 on the shaft 11, with a chain 53 trained about a sprocket 54 on the transmission device power-shaft 55. The sprocket-and-chain drive, between the differential shaft 39 and the power-shaft 29 of the differential 27, is designated 56; while 57 indicates the friction control for the sprocket 40.

In order that the variable-speed friction-device 26 and the associated mechanisms may be electrically-operated and controlled, there is provided appropriate switch stations at both sides of the head-end unit 1, as well as along corresponding locations of the successive cylinder units 1', Fig. IV; it being readily understood that while only one such additional unit 1' has been indicated, and, for convenience, the one most remote from the head-end unit 1, intervening others will be included in the slasher. Each of 45 the switch stations, above referred to, includes "starting", "stopping", "fast", and "slow", switches or push buttons 58, 59, 60 and 61, respectively.

Assuming that the reference numeral 62 designates the connecting and disconnecting knife-switch of 550-v., feed lines 63, 64 and 65, for example, for serving the main drive motor 5; and that 66 indicates a single-pole fused safety switch or cut-out in the feed lines 67, 68, controlling a 110-v., 60 cycle, single-phase magnetic-switch comprehensively designated 69, said cut-out 66 being included in the system as a safety-factor. Now it will be apparent that upon closing the safety cut-out 66 and current connecting 60 knife-switch 62, the operating circuit for the slasher still remains open, and said slasher will remain at rest until one of the several "starting" buttons 58 is pushed-in, as indicated in dotted-lines at the right-hand of Fig. IV, whereupon 65 electric current will flow through the 110-v. feed line 67, closed safety cut-out 66, service lines 70 and splices 70', with the interposed stop buttons 59 to one side or contact 71 of the pushed-in "starting" button 58, across same to 70 contact 71', through line 72 to splice 72', and line 73, to the coil 74 of the single-phase magnetic-switch 69, line 74' and splice 74', to the feed line 68, which results in energizing said coil 74 for closure of the multiple-armed hold- 75

ing-in or solenoid switch 75, which completes flow of current through the lines 63', 64', and 65', to, and sets the main drive motor 5 into operation. After the motor 5 is set in operation, 5 and the pushed-in "starting" button 58 released, flow of current through the coil 74 will be maintained by the now closed holding-in solenoid switch 75 through the medium of the feed line 67, cut-out 66, service lines 70, interposed closed 10 "stop" buttons 59, and splice 70', to the contact 76 and opposing contact 76', branch 73', and splice 73'', coil 74, line 74', and splice 74'', to the line 68.

After the slasher is set in operation as just 15 described, if it is desired to accelerate the same to its maximum operative speed, one of the "fast" buttons 60, as indicated by dotted-lines at the right-hand of Fig. IV, is pushed-in to set in operation the two-speed reversing-motor 15, by 20 excitation of a reversing magnetic-switch 77, actuated through the medium of 110-v. 60 cycle, single-phase multiple-armed solenoids 78, 79. The coil 80 of the reversing switch 77 is energized by current flow from the feed line 67, 25 cut-out 66, service lines 70, splices 70', and interposed "stop" buttons 59, to contacts 76, 76', of closed holding-in switch 69, through branch 73', line 73, coil 74, line 74', to feed line 68. At the same time, current flows from splice 73'', line 30 73 to splice 72', through line 72, across the contacts 81, 82 of the pushed-in "fast" button 60, line 83, to splice 83', of line 84, coil 80, lines 80', 74', and to splice 74'', of feed line 68. By completion of this circuit, the solenoid 78 is attracted 35 into the coil 80, thus completing flow of current from the feed lines 63, 64 and 65 by way of splices 85, 86 and 87, service lines 85', 86', and 87', to the two-speed reversing motor 15, thereby setting the same in motion. Upon release of 40 the pushed-in "fast" button 60, current is diverted to the coil 80 to keep the solenoid switch 78 closed, so that the motor 15 shall continue in operation, by way of the feed line 67, safety cut-out 66, service lines 70, splices 70' and interposed "stop" buttons 59, to the holding-in switch 45 contact 76. From thence the current is conducted, by the contact 76', branch 73', line 73, coil 74, line 74', splice 74'', to the other side of feed line 68, keeping the motor 15 in operation; 50 also from the splice 73'' to line 73, splice 72', to lines 88, 89 and outer contact-bridging "slow" buttons 61, at the left-and-right sides of Fig. IV, to one side contact 90 of the double-throw mechanically-actuated limit-switch 24, thence to the 55 opposing contact 91, line 92, and contacts 93, 94 of the closed magnetic solenoid switch 78, line 84', through the coil 80, line 74', splice 74'', to the feed line 68.

The double-throw limit-switch 24 is conveniently mounted on one side frame 2 and is mechanically actuated, when the "fast" or maximum speed has been attained by being tripped through the medium of a finger 95 on the shaft 17, of the variable-speed device 6, Fig. I, thus 60 breaking the 110-v. 60 c. single-phase circuit, and at the same time moving over to the opposing contacts 96, 97 of said switch, Fig. IV, in an obvious manner. With the circuit through the magnetic switch 77 thus interrupted or broken, 65 the solenoid 78 will become de-energized, thus causing the motor 15 to stop with the slasher operating at maximum speed by the motor 5. In order to reduce the slasher speed, the operator pushes in one of the "slow" buttons 61, thus 70 closing a 110-v. 60 c. single-phase circuit to the 75

solenoid 79. This circuit is completed by flow of current from the feed line 67, through the cut-out 66, service lines 70 and interposed stop switches 59, splices 70', line 73 to contact 98 of the closed "slow" switch 61, as indicated in 5 dotted-lines at the right-hand of Fig. IV; and from thence by the opposing contact 99, line 100, splice 100', line 101, and coil 102, thereby attracting the solenoid 79, with return flow to the line 68 by way of the line 74'. As a result, current supply circuits are closed, by way of the splices 85, 86 and 87, with associated extensions 85'', 86'', and 87'', to the motor 15, for operation 10 in reverse, or reduction of speed, in accordance with known practice. When the "slow" speed 15 for the slasher is attained, it will be readily understood that the last outlined 110-v. 60 c. single-phase circuit will be broken incident to automatic movement of the finger 95, in a reverse direction to that previously set forth, so as to 20 again make contact through the limit switch 24, as explained above in connection with Fig. IV. With the 110-v. 60 c. single phase circuit broken through the solenoid switch 79, the motor 15 will stop and the slasher continue operating at 25 slow speed through the first described circuit from the feed lines 63, 64 and 65.

Now, when one of the "stop" buttons 59, as indicated in dotted-lines at the right-hand side of Fig. IV, is pushed-in, it will be clearly apparent that each of the previously described circuits, in part all depend upon flow of current via the lines 70 across the "stop" button contacts 103, 104; hence by pushing-in any one of said buttons 59, flow of current will be interrupted, 30 and the then holding-in or active solenoid switches 75, 78 or 79, will become de-energized, 35 and the slasher will stop.

From the foregoing it will be apparent that the described differential control renders possible re-setting of the variable transmission of the slasher at any time during building up of yarn *y* on the collecting beam 25, and just as soon as the slasher is thrown back into conventional gearing, such control will automatically bring back the friction 40 45 26 to its original speed, with the requisite amount of slip between said friction and the transmission shaft 39.

Having thus described our invention, we claim:

1. In a slasher including a two-speed drive and a collector beam friction drive; means for gradually and uniformly accelerating or decelerating the two-speed drive from an average-low to an average-high operating-speed for the slasher, or vice versa; and operatively co-ordinated means 50 compensatively controlling the friction drive.

2. In a slasher including a two-speed drive and a collector beam friction drive; automatically-controlled means, including a mechanically adjustable speed limit control, for gradually and uniformly accelerating or decelerating the two-speed drive from an average-low to an average-high operating-speed, or vice versa; and operatively-coordinated means 60 compensatively controlling the friction drive.

3. In a slasher including a two-speed drive and a collector beam friction drive; automatically-controlled means, including a mechanically adjustable speed limit control, for gradually and uniformly accelerating or decelerating the two-speed drive from an average-low to an average-high operating-speed, or vice versa; and operatively-coordinated means including a speed differential for compensatively controlling the friction drive.

4. In a slasher including a two-speed drive and a collector beam friction drive; automatically-controlled means, including a mechanically adjustable speed limit control, for gradually and uniformly accelerating or decelerating the two-speed drive from an average-low to an average-high operating-speed, or vice versa; operatively coordinated means including a speed differential for compensatively controlling the friction drive; and a system of electric wiring including starting, stopping, and speed varying, switches whereby operation of the slasher is controlled.
5. In a slasher, the combination with the collecting beam rotary friction drive, of a compensative control, one side of said control being operated from the friction drive and the other side from the slip means of said friction drive; and means whereby re-setting of the compensative control is effected at any time during the building up of yarn on the collecting beam.
6. In a slasher, the combination with the collecting beam rotary friction drive of a compensative control, one side of said control being operated from the friction drive and the other side from the slip means of said friction drive; a driving shaft for the beam; and means whereby the beam, when thrown back, automatically returns the friction drive to its original speed with the proper amount of slip between said friction drive and the beam driving shaft.
7. In a slasher, the combination with the collecting beam rotary friction drive of a compensative control, one side of said control being operated from the friction drive and the other side from the slip means of said friction drive; a driving shaft for the beam; means whereby the beam, when thrown back, automatically effects return of the friction drive to its original speed with the proper amount of slip between said drive and the beam driving shaft; and means whereby said friction drive is automatically and compensatively controlled.
8. In multiple-cylinder slashers, having a rotary friction drive and an operatively coordinated collecting beam at the head end, the combination of a compensative control including a variable-speed transmission; means whereby the variable-shaft of said transmission is re-set when a yarn filled beam is removed and replaced by an empty one; electric means for operating the slasher; a mechanically-operated limit switch; and electric switch stations for the respective cylinder sections, whereby operation of the slasher from each individual section and the friction drive are automatically controlled.
9. In multiple-cylinder slashers, having a rotary friction device and an operatively coordinated collecting beam at the head end, the combination of a compensative control including a differential and a variable-speed transmission; means whereby the variable-shaft of said transmission is re-set when a yarn filled beam is removed and replaced by an empty one; an electric system including a main driving motor and a two-speed reversing motor, switch stations at each side of the respective cylinder sections, whereby operation of the slasher is controllable from each individual station; and an adjustable limit switch operative, when the slasher attains maximum speed, to effect maintenance of the driving and reversing motors in operation, but when the collecting beam speed is reduced to "slow" to cut out said reversing motor.
10. A multiple-beam slasher as defined in claim 9 wherein the rotary friction device constant drive member is operatively-coordinated to one power shaft of the differential through the medium of a clutch and suitable drive, means for holding said clutch stationary, an endless drive connects the slip side of the friction device to the other power shaft of the differential, and the differential-shaft is operatively coordinated to the adjuster element of the variable-speed transmission, and a suitable drive from said transmission connects with the rotary friction device.
11. A multiple-cylinder slasher as defined in claim 9 wherein the main driving motor and the variable-speed reversing motor are operated from 550-v. feed lines, interposed switches in 110-v. feed lines control differential operating circuits through said motors, and a double-throw limit switch cuts out the variable-speed reversing motor when the slasher is reduced to "slow speed" operation.
12. A multiple-cylinder slasher as defined in claim 9 wherein a mechanically-actuated double-throw limit switch is effective to cut out the variable-speed reversing motor when the slasher is reduced to "slow-speed" operation, and the 110-v. feed lines include a fusible safety switch.
